(57) **CLAIM**

The ornamental design for a self priming hose, as shown and described.

DESCRIPTION

FIG. 1 is a perspective view of a self priming hose according to the present invention;

FIG. 2 is a top view thereof; the bottom, left and ride side views being a mirror image thereof;

FIG. 3 is a front view thereof, and,

FIG. 4 is a rear view thereof.

The broken line showing is included for the purpose of illustrating portions of the article and forms no part of the claimed design.
